FIG. 4

UNITED STATES PATENT OFFICE

2,047,316

MASSAGING AND TREATMENT STOOL

Prentis E. Erickson, Minneapolis, Minn., assignor
to James B. Bradshaw, Minneapolis, Minn.

Application June 10, 1935, Serial No. 25,926

3 Claims. (Cl. 128—33)

This invention relates to improvements in massage treatment stools, and more particularly to a stool provided with a flexible or resilient seat portion which cooperates with a motor driven 5 vibrating applicator normally contacting the under surface of the seat portion of the stool and with a heater for applying heated air directly underneath the said seat portion of the stool.

An object of the invention is to provide an improved massage stool which will be provided with a flexible seat portion, and a vibrating applicator contacting the under surface of the seat portion, and having resilient tensioning means for holding the applicator at the proper pressure against the 15 said seat portion.

Another object of the invention is to provide an improved massage stool which will be provided with a vibrating applicator normally contacting the under surface of the stool seat to vibrate the 20 same and through the seat to vibrate the portion of a patient which is placed in contact therewith, whether it be the feet or parts of the body or legs which contact the seat.

A further object of the invention is to provide 25 an improved massage stool which will be formed with a flexible seat and vibrating and heating devices disposed below the seat, and with a supporting means whereby the seat proper may be tilted at whatever angle desired to best fit the 30 requirements of use.

Other objects will appear as the description 35 proceeds.

In the accompanying drawings which form a part of my application,

Figure 1 is a side elevation of my improved 40 massage stool;

Figure 2 is a top plan view of my improved 45 massage stool;

Figure 3 is a vertical sectional view taken 50 through the stool, on line 3—3 and

Figure 4 is a sectional view taken on the line 55 4—4 of Figure 3.

Like characters of reference are used throughout the following specification and the accompanying drawings to designate corresponding parts.

In carrying out my invention, I provide a massage stool having a seat portion formed with a substantially rectangular frame 1 made from 60 angle iron or any other suitable material, and a resilient and flexible supporting diaphragm forming the seat portion which is disposed within the frame 1, as at 2, and is held therein by suitable fastening means, such as the bolts 3. The diaphragm 2, as shown in Figure 3 of the drawings,

will be extremely full in proportions, so that when a patient is sitting thereon, the seat will be considerably below the line of the frame 1.

Side supporting bars 4 are disposed at the opposite sides of the frame 1, and provided with the lateral lugs 5, which line up with and cooperate with similar lugs 6 at the sides of the said frame 1. The bolts 7 extend through the frame and supporting bars 4 and the associated lugs 5 and 6, and have wing nuts 8 on their outer ends whereby the angular position of the frame 1 may be varied with respect to the supporting side bars 4, as shown in Figure 1 of the drawings. Legs 9 will be attached to the ends of the side bars 4, and terminate in the rubber cushion 15 pads 10.

A supporting bracket 11 is attached at one end of the frame 1 and is provided with a pivoted arm 12, which supports a motor driven vibrator 13, which in turn carries the resilient and pliable 20 applicator 14. Springs 15 connect the arm 12 with the frame 1, for positively holding the applicator in contact with the under surface of the seat portion 2, at all times. An electric switch 16 is positioned on the bracket 11, and regulates 25 the operation of the motor vibrator 13.

A second bracket 17 is supported on the opposite end of the frame 1, and carries the electrical air heater 18, which is controlled by a switch on the said bracket 17, and when turned on, discharges heated air directly upward and on the under surface of the supporting diaphragm forming the seat portion 2 of the stool, thereby giving the benefit of heat with the benefit of the vibrating 30 massage.

As shown in Figure 4 of the drawings, the applicator 14 is formed with a plurality of laterally extending metal springs 19, which are embedded within the pliable rubber or leather covers 20, although other material desired may be employed 40 to cover the spring arms.

From the foregoing description, it will be apparent that my improved massage stool will have many beneficial uses, as when used in contact with the bare feet of a person, or when a person sits directly on the stool, or when the stool is inverted and the upper surface of the seat portion is placed in contact with any portion of the body or legs and arms. Especially the massage stool 45 is very helpful for women patients to relieve pains due to menstruation. Neuralgia or any muscular pains and aches are relieved with the use of my improved stool, and as it restores circulation to the parts being treated and with the application 50 55

of heat at the same time, congestion and colds are relieved.

Many minor changes in details of construction may be resorted to without departure from the spirit of the invention.

Having thus described my invention what I claim as new and desire to secure by Letters Patent of the United States is:

1. A massage stool having supporting means, a seat frame pivotally mounted on said supporting means and formed with a flexible and elastic supporting diaphragm forming the seat portion, a vibrator disposed below said diaphragm and in contact therewith, and a plurality of resilient laterally extending fingers encased in a suitable covering on said vibrator and in contact with the under surface of said diaphragm.
- 10 2. A massage stool having supporting means, a seat frame pivotally mounted on said supporting means and formed with a flexible and elastic

supporting diaphragm forming the seat portion, a vibrator disposed below said diaphragm and in contact therewith, a plurality of resilient laterally extending fingers encased in a suitable covering supported by said vibrator, and resiliently tensioned means for holding said vibrator in contact with the under surface of said diaphragm. 5

3. A massage stool having supporting means, a seat frame pivotally mounted on said supporting means and formed with a flexible and elastic 10 supporting diaphragm forming the seat portion, a vibrator disposed below said diaphragm and in contact therewith, said vibrator having a plurality of resilient laterally extending fingers encased in a suitable covering, resiliently tensioned 15 means for holding said fingers in contact with the under surface of said diaphragm, and an air heater supported on said supporting means directly below said diaphragm.

PRENTIS E. ERICKSON. 20
